UNITED STATES PATENT OFFICE.

BURNHAM C. STICKNEY, OF RUTHERFORD, NEW JERSEY, ASSIGNOR TO UNDERWOOD
TYPEWRITER COMPANY, OF NEW YORK, N. Y., A CORPORATION OF DELAWARE.

TYPEWRITING MACHINE.

Application filed July 12, 1924. Serial No. 725,536.

This invention relates to improvements in typewriting machines of that type where-
in a fan-folded web is designed to be fed along to printing-line position, while per-
mitting manifolding ribbons to be inserted
5 between the plies of the fan-folded web.

The slitting of the several folds of the fan-folded web is effected before the slitted portions of this web are carried around the
10 platen or between said manifolding ribbons.

The slits are co-extensive with the length of each form printed upon this web.

There is eliminated any tendency of the slitted portions of the fan-folded web from
15 creeping as they are carried around the platen along to the printing line of the machine and to the manifolding ribbons sta-
tioned at this point. The use of sheets of carbon heretofore usual in fan-fold type-
writers is rendered unnecessary, and the
20 same is true of the devices for lifting up the platen to straighten out the work-web preparatory to stripping the usual carbons.

Other features and advantages will here-
25 inafter appear.

In the accompanying drawings,

Figure 1 is a longitudinal sectional elevation of the invention positioned upon a type-
writing machine.

30 Figure 2 is a top plan view thereof.

Figure 3 is a fragmental view of a web showing a knife blade in engagement therewith.

Figure 4 is a fragmental view of the rib-
35 bon-support.

Figure 5 is a diagrammatic view, showing the manner in which the alternately oppo-
site folds of the web are slit at the same time.

40 In the drawings, which are merely illus-
trative of this invention, A and B designate the sides of a platen-frame of a typewriting machine, such as the Underwood, which is provided with means for carrying a fan-fold web C with printed forms thereon to a manifolding device located at the printing line of the machine. A platen-shaft 10 is mounted in suitable bearings upon the frame sides A and B, and carries platen 11.

45 50 12 designates a hand-wheel for rotating the platen, and 13 and 14 designate the front and rear pressure rollers.

A paper-shelf 15 at one end 16 is curved upwardly, while the other end provides a
55 curved downwardly-extending ledge 17 over

which the web C is carried. By means of cleats 18, the paper-shelf 15 is operatively secured to the under side of the frame por-
tions A and B, and as thus positioned the shelf is preferably inclined downwardly so
60 that its curved end 16 is arranged concentrically with the under side of the platen in spaced relation thereto.

The paper-shelf 15 has opposing longi-
tudinal edges pressed or struck upwardly in
a manner to provide upstanding tracks or
rails 19 right angular in cross-section. That
end of the paper-shelf which is in a plane
with the ledge 17 is suitably slit so as to
permit the guide-lips 20 to be formed in up-
70 standing relation on the shelf nearer the
center thereof than are the tracks or rails
19, these guide-lips permitting the usual
width of the web C to be guided along over
the shelf 15, as shown particularly in Fig-
75 ure 2.

The type-bars 21 have types 22 which strike through main typewriter ribbon 21^a, which vibrates in the usual manner adjacent the front side of the platen 11. A pair of 80 plates 23 is positioned upon the upper sides of the platen-frame A and B, respectively, and held in secure position by fasteners 24, and a bar 25 which extends completely across the machine is also secured by fasteners 24 85 in contact with the plates 23. This bar pro-
vides a support which at a medial point is struck upwardly to provide a lug 26, which is preferably inclined, as shown in Figure 1, and has secured thereto the lower end of 90 a shelf-bar 27, which is inclined rearwardly with respect to the front plane of the platen. A paper-gage 28 is slidably mount-
ed upon the shelf-bar 27 and is held in any
adjusted position thereupon by means of 95 the thumb-screw 29. This gage carries an abutment 30 against which may be set the free leading ends of the typed portions or plies of the web in a manner and for a pur-
pose well known to those skilled in the art.

Depending downwardly substantially at right angles to the plates 23 are arms 31, which confront the opposing ends of the platen 11. Projecting down along the inner sides of the frame portions A and B, these 105 arms are formed with terminal hooks 32 around which are held and supported loops 33 formed or secured upon the outer ends of a plurality of typewriter ribbons 34, which ribbons are thus held in alignment so as to 110

extend longitudinally across the platen contiguous thereto. These interposed ribbons are mounted on the Underwood letter-feeding platen-carriage and travel therewith.

- 5 There is a web-severing knife bar or blade 35 permanently fixed in position immediately over the typewriter ribbons, as shown in Figure 1, being supported at the same inclination as the shelf-bar 27, so as to guide 10 the typed portions of the plies of the web beyond the typewriter ribbons and over the platen onto the shelf-bar 27, whereupon the web may be measured to a predetermined length and then drawn over the knife edge 15 of the bar 35 and severed from the untyped portion of the web. The knife bar 35 is provided with ears 36, which are secured by fasteners 37 to the arms 31 of the plates 23.
- 20 Positioned for slidable engagement with the rails or tracks 19 of the paper-shelf is a fold-slitting and web-looping carriage 38 consisting preferably of a strip extending transversely of the shelf 15 and provided at 25 its opposite ends and at points spaced from the longitudinal edges of the web with grooved wheels or rollers 39, which are suitably mounted upon trunnions 40 secured to the carriage 38, a slidable stop 41 being oper- 30 atively arranged to slide upon one of the rails 19 and locked by means of a thumb-screw 43. Brackets 44 are secured upon the ends of the carriage 38 adjacent the rollers 39 and carry pins 45 upon which are ful- 35 crumed the lever arms 46 which support a pressure bar 48 that extends completely across the effective width of the fan-folded web C, which latter is guided between the upstanding guide-lips 20. Collars 47 on the 40 pins 45 hold the lever arms 46 in proper position upon said pins. Suitable springs 49, preferably leaf-springs, are provided having central coils 50 linked over the pins 45, and having terminals 55 fixedly secured to 45 projections 54 secured to the brackets 44 and having their free terminals hooked over the lever arms 46, as shown clearly in Figure 1, and thus urged to apply yieldable tension upon the pressure bar 48, which is 50 preferably formed concave in cross-section throughout its length to avoid injury to the web upon which it presses. Also secured to the opposing ends of the carriage 38 in a plane with the lever arms 46 are a plurality 55 of knives or knife blades 51, which are secured by fasteners 53 engaging the shanks of these knives, the blades themselves inclining so as to provide two sets of blades arranged vertically in staggered relation and 60 converging toward the center of the pressure bar and beyond the inner sides of the guide-lips 20 toward the center of shelf 15 to assure that these knives may project into bights or folds, E of the web C at the required points. A handle 41^a is operatively

secured to the carriage 38 at 42 by means of which the carriage may be impelled manually up and down the paper-shelf 15, first to slit the folds and then to form a loop in the slitted web.

70 In operation, the web is carried from its position in a tray beneath the machine (not shown) over the ledge 17 of the paper-shelf 15 between the guide-lips 20, and is also carried around the under side of the platen and 75 inserted with its plies between the typewriter ribbons 34 and then moved through the mouth formed by the knife 35 and adjacent surface of the platen 11 over upon the shelf-bar 27. The length of each form 80 printed on the web C being known, the gage 28 is placed in its proper adjusted position, so as to measure off this same length prior to the typed printed forms being severed along the knife edge 35. Pressure rollers 13 85 and 14 hold the web against the platen. The normal position of the slitter is shown in dotted lines immediately in back of the platen where the pressure roller 14 engages the latter in Figure 1.

90 Now while the tensioning rollers 13 and 14 are holding the web at one point, the slitting knives 51 project through the bights E of the web wherever necessary, as shown clearly in Figure 5, some of the knives projecting through the folds at one side and others at the other side of the same web to be sure that all of the webs will be slit simultaneously to separate the plies therefrom. The slitter carriage being thus initially positioned with its knives ready for action, the operative grasps hold of the handle 41^a and steadily moves the slitter carriage away from the platen until the carriage contacts with the stop 41, at which point the entire 100 length of the printed form thereon has been traversed by the slitting knives 51, which, as shown in Figure 3, have slit the edges or bights of the web throughout predetermined lengths. As the slitter carriage 105 travels back during this slitting operation, the pressure bar 48 may bear down smoothly under tension upon the web in advance of the knives, thus smoothing the web as the knives perform their slitting action, and this pressure exerted by the pressure bar 48 is less than the tensioning pressure of the tensioning rollers 13 and 14, so as not to prevent the web from being held fast at this point.

110 The carriage 38, while the pressure bar is still in engagement with the web, is next caused manually to return to initial position, and during this return the pressure bar carries the web along with it and slackens it, thus converting the entire length of the printed form already slit into the loop D, shown in Figure 1, which loop is completely formed after the carriage comes to rest in initial position, and which loop is 115 120 125 130

located immediately in back of the platen 11.

During the typing of the next form, the slitted loop portion of the web is taken up 5 while the plies advance line by line between the several typewriter ribbons 34, so that the plies may receive manifold impressions in the usual manner. The loop D is gradually taken up, and thereupon the operation al- 10 ready described is repeated, and while the tensioning rollers 13 and 14 are holding the web still at the point where it engages the stationary inactive platen, the carriage is again moved away from the platen to slit 15 a fresh printed form on the web, etc.

It will be seen from the above description that, during the typing of the several slitted plies of the fan-folded web, the carriage remains stationary, and that during 20 the progressive advancement of the slitted portion of the same during the line-spacing action of the platen no creeping of the plies will occur inasmuch as said plies remain integrally joined at their folds down to within 25 a short distance of the printing point.

Variations may be resorted to within the scope of the invention, and portions of the improvements may be used without others.

Having thus described my invention, I 30 claim:

1. In a typewriting machine, as described, the combination of a frame, a platen mounted thereupon, a fan-folded web carried around said platen, means for supporting manifold- 35 ing ink ribbons between the web-plies in front of said platen, a paper-shelf over which said web is fed, said paper shelf fixed to the platen frame, a plurality of knife-blades projecting between the plies of said web, to 40 separate said plies preparatory to threading of the plies between said ribbons, means for maintaining said knife-blades in slide- 45 able relation with said shelf, and means for driving said knife-blades back from the platen to slit the bights of said web.

2. In a typewriting machine, as described, the combination of a frame, a paper-shelf inclining toward and supported upon said frame, a platen mounted in said frame at 50 the foot of said shelf, said paper-shelf fixed to the platen-frame, a fan-folded web being fed down along said shelf, over and around said platen, means for supporting manifold- 55 ing ink ribbons between the web-plies in front of said platen and nested between the plies of said web, means for moving rear- 60 wardly from the platen a plurality of knives to slit the folds of said plies preparatory to threading of the plies between the ribbons, and a friction-device movable with said knives, and engaging said web, and during the return movement of said knives operating to loop said web in back 65 of said platen.

3. In a typewriting machine, as described,

the combination of a frame, a shaft therein, a revolute platen mounted permanently upon said shaft, and against vertical move- 70 ment, a fan-folded web progressively fed under and around the front side of said platen, a plurality of manifolding strips operatively positioned adjacent said platen, between which the several plies of said web may contact, means movably supported rear- 75 wardly of said platen, for slitting the folds of said web during a rearward motion of said means with respect to said platen, and a friction-device carried by said means, and feeding said web along with it during a motion of said means in the direction of 80 said platen, whereby the web is placed under slack immediately in back of said platen.

4. In a typewriting machine of the kind described, the combination with a frame, of a platen permanently mounted therein, mani- 85 folding means permanently mounted at the front of the platen, a paper-shelf arranged so as to extend upwardly and rearwardly at the intake side of said platen, a fan-folded web fed upon said shelf under and around said platen, pressure-rollers maintaining ten- 90 sion upon said web, and pressing the latter in engagement with the platen during the fold slitting operation, means engaging the folds of said web, for slitting the same as it moves towards the rear of said shelf, a tension-device movable in unison with said slitting means, and drawing out the web as it moves rearwardly of the platen, but effective to carry said web along to slacken the same immediately in back of the platen as it returns towards said platen, and means for adjustably limiting the rearward move- 95 ment of said slitting means.

5. In a typewriting machine having a platen, and a platen-frame, the combination of a manifolding equipment supported on said platen-frame, said manifolding equip- 100 ment in the form of means for supporting a set of ink-ribbons between web-plies at the printing line on the platen and in front thereof, a fan-fold web slitting device on the intake side of the platen and immedi- 105 ately in rear thereof, and means to move said slitting device back from the platen independently of said manifolding equip- 110 ment, to slit the folds of the web prepara- 115 tory to the passage of the web through said manifolding equipment.

6. In a typewriting machine having a platen, and a platen-frame, the combination of a manifolding equipment supported on said platen-frame, said manifolding equip- 120 ment in the form of means for supporting a set of ink-ribbons between web-plies at the printing line on the platen and in front thereof, a fan-fold web slitting device on the intake side of the platen and immedi- 125 ately in rear thereof, and means to move said slitting device back from the platen 130

- independently of said manifolding equipment, to slit the folds of the web preparatory to the passage of the web through said manifolding equipment, and a paper-grip-
5 per connected to said slitting device and effective to grip the web in rear of the slitting device and during the return of the slitter to form the web-plies into a loop immediately in rear of the platen.
- 10 7. In a typewriting machine, the combination with a frame, of a platen revolvably and permanently mounted therein, a paper-shelf extending toward said platen at the intake side thereof and permanently mounted on said platen-frame, a fan-folded web movable along said shelf under and over said platen, a slitting member slidably engaging said paper-shelf, and having knives projecting between the several folds of said web, said knives effective to slit said folds only as the slitting member moves away from said platen, tensioning means located underneath said platen, and effective to hold the web at this point during the fold-slitting
25 operation, a tensioning device connected to said slitting member for stretching said web during the slitting action of said member, but effective, upon the return of said member, to carry the web along with it, so as to form a loop, immediately in back of said platen, to be taken up by said platen, and a plurality of manifolding strips permanently mounted in front of said platen, through which the slit plies of web are
35 threaded.
8. In a typewriting machine of the kind described, the combination of a platen revolvably mounted therein against independent movement, a fan-folded web movable towards, under and over said platen, means movably projecting between the plies of said web, normally stationed immediately in back of said platen, a tensioning device pressing said web against said platen to hold it against movement, said means drawing said web out as it moves away from said platen, slitting knives carried by said means for severing the plies of said web during the mentioned movement of said means, said
45 means looping the portions of the web slit by it as it returns to normal position, and a device supporting a plurality of aligning ribbons adjacent said platen in advance of said tensioning device, said platen, upon rotating, taking up the looped slit portions of the web and carrying the same between said ribbons.
9. In a typewriting machine, the combination with a frame, of a platen-shaft mounted therein permanently, a platen on said shaft, a pair of brackets hanging from the opposite sides of said machine and confronting the ends of said platen, a plurality of manifolding strips operatively supported upon said brackets, so as to extend in longi-
60 tudinal alignment contiguous to said platen, a fan-folded web adapted to be actuated by said platen, so as to pass with its plies between said manifolding strips, typing mechanism engaging the manifolding strips against the plies of said web simultaneously, a paper-shelf inclining downwardly, and having its lower end arranged concentrically under said platen, means carried at the rear of said shelf, providing guides for the longitudinal edges of said web, slitting means held in slidable engagement with said shelf, and normally positioned immediately to the rear of said platen, said slitting means being manually actuated to move rearwardly of said platen and to slit the folds of said web, tensioning rolls holding said web against movement and in contact with said platen as said slitting means performs its slitting operation, and a web-looper carried by said slitting means for looping the already slit portions of said web, said platen taking up the slit loop portions of said web, the take-up action of said platen and slitting action of said slitting means being alternate.
65
10. In a device of the kind described, a paper-shelf consisting of a sheet-metal base-plate having its longitudinal edges upstruck in angle-iron formation to provide longitudinal tracks, the rear edge of said base-plate being slit and curved so as to project downwardly, and integral portions struck out from the curved rear edge of said base-plate, and providing a pair of guides immediately in back of said tracks, the front portion of said shelf projecting beyond said tracks and being formed arcuate.
70
11. In a device of the kind described, the combination of a paper-shelf, a carriage rolling thereupon, means for guiding said carriage along a predetermined path upon said shelf, a pressure-bar disposed longitudinally upon said carriage, lever-arms supporting the opposite ends of said pressure-bar, means fulcruming said lever-arms upon said carriage, and means yieldably exerting spring pressure upon said lever-arms to hold said pressure-bar in frictional tension with said shelf as the carriage moves thereover.
75
12. In a device of the kind described, the combination of a paper-shelf, rails carried longitudinally of, and in spaced-apart relation upon, said shelf, a carriage consisting of a sheet-metal strip extending across said shelf, and carrying rollers engaging said rails, brackets secured to the opposite ends of said carriage, fulcrum-pins secured into said brackets, lever-arms fulcrumed upon said pins, and having outer terminals curving downwardly, the pressure-bar extending longitudinally of said carriage, and secured upon said lever-arms, said pressure-bar being concave in shape throughout its length, and coil-springs secured upon said brackets,
80

- and having terminal fingers looped over said lever-arms, exerting tension thereupon to force the pressure-bar into engagement with the carriage.
- 5 13. In a device as described, in combination, a revoluble platen, a web movable into contact with said platen, a manifolding device carried at the printing line of said platen through which said web is advanceable, over said platen, mechanism for slitting said web rearwardly of said platen, and means controlled by said mechanism for looping the slit portions of said web prior to the advancement thereof to said manifolding device.
- 10 14. In a typewriting machine, in combination, a platen revolvably mounted therein, a paper-shelf supported under said platen and extending rearwardly therefrom, a Ian-
folded web traversing said shelf lengthwise 20 and engageable by said platen so as to be fed thereover, a plurality of ink-ribbons disposed at the printing line of said platen and having a nested relation with the plies of said web, said web having its folds all slit 25 before carried over said platen, a tearing-off knife stationed adjacent said platen immediately above said ink-ribbons, said web being inscribed with a consecutive number of printed forms of equal length, means for 30 manually looping each slit form, said platen picking up said loop and carrying the same beyond the tearing-off knife for the shearing of the printed form thereby, and means 35 yieldably engaging said web adjacent the tail end of said loop for holding the looped portion of said web against lateral creeping.

BURNHAM C. STICKNEY.
